INVENTOR.

BY

Watson E. Coleman

ATTORNEY.

UNITED STATES PATENT OFFICE.

CHARLES A. SCHMITT, OF ANACONDA, MONTANA.

WINDOW FASTENER.

Application filed May 20, 1921. Serial No. 471,031.

To all whom it may concern:

Be it known that CHARLES A. SCHMITT, a citizen of the United States, residing at Anaconda, in the county of Deerlodge and State of Montana, has invented certain new and useful Improvements in Window Fasteners, of which the following is a specification, reference being had to the accompanying drawings.

10 This invention relates to window fasteners and has for its object to provide a device of this character which not only locks the window but holds it in any position desired.

15 Another object is to provide a window fastener of this character which is automatically operable to lock the window and manually operable to permit movement of the window in the desired direction.

20 Another object is to provide a window fastener of this character including a pair of locking bolts adapted to engage a rack carried by the window frame, the locking bolts being constantly urged into engagement with the rack to prevent movement of the window and operable alternately to permit movement of the window in the desired direction.

25 A still further object of the invention is to provide a fastener of this character including a pair of locking bolts and means for alternately operating said bolts whereby one of the bolts is retracted to permit the remaining bolt to ride freely over the rack upon movement of the window in the desired direction.

30 With the above and other objects in view, the invention consists in the improved construction and arrangement of parts to be hereinafter more particularly described, fully claimed and illustrated in the accompanying drawings, in which:—

35 Figure 1 is a view in elevation of a window frame and sash showing the invention applied,

40 Figure 2 is a side elevation of the lock, with one side of the lock casing removed,

Figure 3 is an end elevation, and

45 Figure 4 is a side elevation showing one of the movements of the lock.

Referring to the drawings, A designates a window frame and B the window sash. Disposed within one of the stiles of the window frame A is a rack 5, said rack having

50 substantially V-shaped teeth to permit lock-

ing of the window either in its raised or lowered position. This rack is secured by means of screws 6 and is countersunk within the stile of the window frame so as to permit unobstructed movement of the window. 60

In order to secure the window in various positions, there is provided a novel form of fastener comprising a casing 7, one end of the casing being closed by a plate 8 having a plurality of aligned slots 9. The 65 casing 7 is adapted to be countersunk in one of the rails of the window sash so that the outer face of the plate A lies flush with the rail of the window sash to eliminate projections and prevent resistance to 70 the movement of the window sash. A pair of latch bolts 10 are provided, the end 11 of each bolt being pivoted within the casing 7 while the end 12 is bevelled and intended to move through the slot. It will be noted 75 that the slots 9 are relatively long so as to permit lateral movement of the ends 12 of the bolt upon actuation of the lock.

The latch bolts 10 are normally held in their extended or locked position by means 80 of a spring 13, said spring being substantially semicircular and having its ends engaged with the bolts so as to normally hold them in engagement with the inner end walls of the slots 9. When the bolts are in this 85 position it is impossible to move the sash in either direction, as the ends 12 are disposed firmly in engagement with the teeth of the rack 5. In order to permit movement of the sash in the desired direction, 90 there is provided a novel form of tumbler 14, the tumbler having oppositely extending fingers 15, each of which is arranged to engage one of the bolts 10, the body portion of the tumbler adjacent the finger 15 95 being cut away to receive the pivotal ends 11 of the bolts. The tumbler 14 is provided with a socket member 16 which projects beyond the sides of the tumbler and through the sides of the casing to serve as trunnions 100 for the tumbler. A stem 17 extends from the end wall of the socket in spaced relation to the side walls thereof and is adapted to properly position the operating member 18 by means of which the lock is actuated. 105

In the operation of the device, as previously stated, the bolts are normally maintained in the position shown in Figure 2. If it is desired to raise the window, the operating member is inserted in the socket 16 110

- 2
- and turns toward the window sill, thereby swinging the uppermost bolt within the casing and permitting the lowermost bolt to slide similar to a ratchet over the rack 5.
- 5 Any tendency of the window to descend will of course be arrested by the lowermost bolt as it will not permit downward movement of the window when engaged with the rack. When the operating member 18 is 10 released the uppermost bolt automatically swings into engagement with the rack, thereby preventing further movement and cooperating with the lowermost bolt to prevent movement in either direction. When 15 it is desired to lower the window, the operation is reversed, the lowermost bolt is swung inwardly of the casing by means of the tumbler 14 and member 18 so as to permit the uppermost bolt to slide over the rack 20 until the window reaches the desired point.

An important feature of this window fastener is that it not only securely locked the window in any position but also eliminates the use of sash weights as it is impossible 25 for the window to accidentally descend when this lock is applied as it does not depend on the operator to lock the same but works automatically. In addition to this the member 18 is relatively large so as to permit 30 a firm grip to be obtained and not only operates the lock but provides a handle for the raising and lowering of the window. Furthermore, it is impossible for this lock to be picked or manipulated from the out- 35 side as it is practically concealed within the rail of the window sash.

Another important feature is that the

bolts 10 do not slide but swing inwardly and outwardly of the casing, the ends 12 being rounded so as to permit the bolt to 40 move freely through the slot without coming in contact with the casing, and the lock only requires the use of one tumbler for its 45 operation. All of these features are possessed by a device that is compact and simple in construction.

What is claimed is:—

A window fastener of the character described comprising a casing having spaced openings in one end wall thereof, bolts pivoted in said casing at one of their corresponding ends and extending through said openings substantially in divergent relation to each other, a tumbler journaled within the casing beyond the pivoted ends of the 55 bolts and substantially between said pivoted ends and the opposite end wall of the casing, the shank of said tumbler extending between and inwardly of the pivoted ends of the bolts, the free end of said shank having 60 fingers projecting therefrom in opposite directions for engagement with the intermediate portions of the bolts, and a leaf spring disposed within said casing and substantially embracing the tumbler and the pivoted end portions of the bolts, the end portions of said spring being adapted to engage the intermediate portions of the bolts 65 remote from the intermediate portion of the bolts engaged by the fingers of the tumbler. 70

In testimony whereof I hereunto affix my signature.

CHARLES A. SCHMITT.
